UNITED STATES PATENT OFFICE

JOHN ARBOSUCKOS, OF CARNEGIE, PENNSYLVANIA

SEWER CLEANER

Application filed March 9, 1931. Serial No. 521,386.

This invention relates to an apparatus and method for cleaning and opening sewers, pipes, drains, sinks, conduits, traps and the like and for removing obstacles, sewage, and 5 other blocking substances therefrom by the application of steam under pressure.

One of the objects of the invention is to provide a portable device for quickly building up a quantity of steam under pressure and 10 having suitable means for application of such steam to the sewer or blocked drain that is to be opened.

Other objects of the invention will be apparent as the invention is hereinafter described and explained.

It has been customary heretofore to place lye and other corrosive chemicals in sewer pipes and drains to try to dissolve grease, dirt and other obstacles in an effort to open the 20 same to a clear passageway. Not only are these chemicals more or less dangerous to handle on account of their burning and corrosive action to the operator's skin, eyes, etc., as well as attacking floor paint, woodwork, 25 etc., but they are also inefficient at times and not wholly reliable. Furthermore when the blocking refuse is not close to the working end of the pipe, the chemicals are weakened and diluted in strength by the time they reach 30 the obstacle. This often necessitates the use of complex devices for boring and rotating long wires thru the entire drain or pipe by mechanism requiring more than one man for operating, or may require the actual excavation 35 of the pipe for removal and cleaning.

My invention obviates these disadvantages in that it provides a small portable apparatus that can be manned and operated by one 40 person without danger of being burned by chemicals nor without danger of marring furniture, walls, floors, or paint by its use. Furthermore, it is simple in operation, requiring but a few minutes to place in service, 45 and the results are sure and reliable, thus preventing expense, delay, discomfort and the possible continuance of unsanitary conditions, which are so repulsive to those of refinement.

My preferred apparatus is indicated in the 50 accompanying drawings.

Figure 1 is a view in side elevation showing the adapter in bottom plan.

Figure 2 is a plan view of the device shown in Figure 1.

Figure 3 is a sectional view of the device 55 shown in Figure 1 with the adapter in full view.

Figure 4 is a transverse section taken along the line 4-4 of Figure 3.

Figure 5 is a view in elevation of a modified 60 type of adapter.

Referring to the drawings:

The numeral 1 is an outer casing having perforations 2 therein at its conical shaped top portion. Housed within the outer casing 1 is the steam generating member 3 adapted to contain water and spaced from the casing 1 by the spacing clips 5, thus forming a circumferential passage 6 therebetween. The steam generator 3 is of cylindrical construction and has a cone-shaped top 7 corresponding to the cone top of casing 1. The generator 3 is provided with a vertical cylindrical recessed portion 8 in the body thereof extending from an open end at the base of the generator upwardly to communicate with a number of horizontally disposed transverse passages 9, which passages communicate in turn with the outside passage 6. A water gauge 10 passes thru both outer casing 1 and generator casing 3 at the upper end thereof. A water supply conduit 11 carrying funnel 12 and cock 13 passes thru outer casing 1 and generator 3, and is disposed vertically to the bottom of the generator. The steam exit pipe 14 passes thru the apices of the cones of generator 3 and casing 1 and has a flexible hose or tubing 15 connected therewith. An adapter 16 is suitably joined to the flexible hose 15 by any suitable means such as nut 17. If desired, adapter 16 can be replaced by any other suitable adapter 18, as shown in Figure 5. A flame shield 19 provided with spring clips 20 detachably secured to outer casing 1 by means of complementary receiving sockets 21 therein, prevents any suitable torch 22 from being blown out and also conserves radiated heat.

The operation of my device is as follows: The pet cock or valve 13 is opened and a

suitable amount of water is poured into funnel 12 until the water shows a level higher than the lower end of the gauge. The valve 13 is closed, and the adapter 16 inserted into the pipe to be cleared. Heat is applied to the generator by a suitable torch at its base. The generator is heated directly and also by the hot air currents passing upwardly thru the vertical passage 8, transverse passages 9 and circumferential passage 6. The products of combustion as well as the air deprived of most of its sensible heat pass out thru the perforations 2 in the top of the casing. A mixture of steam and boiling water, both under pressure, is thus forced thru the hose 15, adapter 16 into the blocked drain pipe. This mixture of steam and water under pressure quickly and efficiently clears the blocked drain in a few minutes.

29 The adapter 16 preferably comprises a steel cone-shaped plug provided with a rubber washer secured thereto by a steel plate at the bottom thereof. A bolt below the steel plate screws upwardly in cooperation with a thumb 25 or wing nut bolt screwing downwardly, thus making the cone and plate fit tightly against the washer. The adapter 16 is preferably used for cleaning a four inch sewer pipe. For a 1½ inch diameter pipe, I prefer to use 35 the adapter 18 as shown in Figure 5. In this case, it is provided with a rubber washer 22 of about 2 inch diameter and the whole adapter is capable of being held down by hand until the pressure breaks thru the pipe.

55 My generator is adapted to hold about 6½ quarts of water or other liquid and is about 10½ inches high and 7½ inches in diameter. The outer casing has a diameter of about 8 inches, and the entire device weighs about 25 40 pounds. The brackets 5 are preferably made of copper and soldered, brazed or welded to the generator to keep the same firmly in place. The shield 19 is preferably about 12 inches high.

45 As will be understood, the circulation of the heat thru the various passages gives greater efficiency. The number of passages can be increased, if desired. The water gauge 10 may be dispensed with, but I prefer to 50 have it. Similarly, the water supply pipe may be suitably positioned at another part of the device.

55 I have found that a passage can be cleared in a four inch pipe in about ten or fifteen minutes.

Having described my invention in accordance with the provisions of the patent statutes, what I claim is:

60 A portable device for cleaning drains and 65 the like comprising in combination a cylindrical shell open at its base and closed at its top with a cone-shaped perforated cap, an inner steam cylindrical generator member having a cone-shaped cap and disposed with- 70 in the outer shell and spaced therefrom to

provide a substantially unrestricted circumferential passage therebetween, the generating member being provided with a vertically disposed inner cylindrical member defining a recess opening in the bottom portion of the generator, a plurality of horizontal tubular members disposed radially about the inner cylindrical member and defining communicating passages from the recess to the circumferential passageway, means for supplying liquid to the generator, means for removing steam to the drain to be cleared, and a cylindrical flame shield detachably secured to the outer shell and serving as a standard for the apparatus, said outer shell having sockets therein and said flame shield having spring fingers arranged to engage in said sockets.

In testimony whereof, I hereunto set my hand.

JOHN ARBOSUCKOS.
